X-RAY SIMULATING TOY

Charles S. Raizen, New Rochelle, N. Y.

Application October 12, 1949, Serial No. 120,857

2 Claims.

(Cl. 46—1)

1

My invention relates to optical toys or to toys producing optical illusions, and one of its objects is to provide simple and inexpensive means for simulating the effects of an expensive apparatus.

Another object is to simulate the effect of X-rays.

A further object is to simulate the effect of a microscope.

Still other objects are to provide one device for optionally simulating the effect of X-rays or of a microscope, thereby to provide a toy for various interesting and educational uses, to facilitate the adaptation of the toy for one of these uses and the change from one use to the other, and to indicate clearly the use for which the toy is set at a time.

Still other objects and advantages will appear from the following description of an exemplifying embodiment of my invention, from the appended claims and from the accompanying drawing in which:

Fig. 1 shows a front view of an illustrative embodiment of my invention.

Fig. 2 shows a cross-section taken along the line 2—2 in Fig. 1.

Fig. 3 shows a front view of a frame which is a part of the embodiment shown in Figs. 1 and 2.

Fig. 4 shows another view of the same frame seen from the lower side in Fig. 3.

Fig. 5 shows a front view of a broken off portion of a film band or picture strip which may be used as a supplementary part of the embodiment shown in Figs. 1 to 4.

Fig. 6 shows an optical illusion which may be produced by the embodiment shown in Figs. 1 to 4.

Referring to the drawing, numeral 1 indicates a casing which is similar to a camera and has a front wall 3, a back wall 4, two side walls 5, a top wall 6 and a bottom 7. The bottom 7 may be provided with a stem-like extension 8 which simulates the foot piece of a camera and serves as a handle. The front wall 3 has an about centrally located circular peep-hole 9 and another aperture 11 which is preferably positioned vertically over the hole 9 and may have a rectangular shape. The back wall 4 has a window or opening 12 which is positioned opposite to the look-hole 9, is preferably considerably larger than the latter and may have a rectangular shape.

A frame 13 comprises a central portion 14 and two wings 15 extending symmetrically from the central portion to opposite sides. Each wing has a flat rectangular cross-section and passes slidably through correspondingly shaped slots in one of the side walls 5. The central portion 14 is thicker and higher than the wings 15 and is

2

shorter, in the sliding direction, than the distance between the side walls 5. Hence the frame 13 can slide from a position where the portion 14 contacts one of the walls 5 to a position where this portion contacts the other wall 5. The casing 1 may be made of parts of any suitable shape which are integrally united after the frame 13 has been inserted.

The central frame portion 14 has a rectangular recess 16 in its front and a similar recess 17 in its back. Two layers 18 which may be made of cardboard are tightly inserted in the recess 17. Windows or peep-holes 19 and 21 form openings passing through the portion 14 and through the layers 18. These windows are positioned at the same level, and their centers have a distance equal to the sliding way of the frame 13 from one of its extreme positions to the other. When the frame is in its extreme right position as shown in Fig. 1 in full lines, the window 19 is co-axial with the peep-hole 9. When the frame is in its extreme left position indicated by dotted lines in Fig. 1, the window 21 is co-axial with this peep-hole.

25 The front of the frame portion 14 comprises a surface area 22 which shows two different indicia or legends. For example, an indicium reading "X-Ray" is positioned vertically over the window 19, and an indicium reading "Red-Ray" is positioned vertically over the window 21. Both indicia are positioned at the same level as the aperture 11.

Two different transparent layers 23 and 24 are positioned across the respective areas of the windows and may be wedged between and affixed to the layers 18. The layer 23 spanning over the window 19 is a piece of feather which may be cut out of the fan portion of a suitable bird feather, for example, of a chicken feather, or 40 may be an artificial imitation of such a feather portion. This layer forms a coherent area of not uniform transparency, brighter portions being interrupted by narrow darker lines. I have found that the particular structure of such a feather 45 produces an effect adapted to simulate an X-ray picture as will be described later.

The layer 24 is a transparent sheet of uniform color and serves to simulate the effect of a microscope as will be described later. When the 50 described toy is used for the latter purpose, a transparent picture is observed through the layer 24. A number of suitable pictures may be arranged for alternate or selective use in a row on a transparent strip or film band 25. For 55 example, a field 26 of this film contains one picture and further fields 27 may contain other pictures. Each of these pictures comprises two

different representations, one showing an object that is ordinarily well visible with the naked eye or a macroscopic object, the other representation showing a microscopic object, that is, an object that is ordinarily visible only under a microscope. The microscopic object is represented on a considerably larger scale than the macroscopic object and about as large as it would appear under a microscope. For example, field 26 shows a hand 28 which is a macroscopic object and germs 29 which are microscopic objects.

The macroscopic and microscopic objects are represented in overlapping positions and in different colors. The color of the macroscopic picture is the same as that of layer 24, for example, red. The color of the microscopic object is preferably a contrasting or complementary color, for example, green or blue. The color of the microscopic object is preferably less dark or less intense than the color of the macroscopic object.

The casing 1 is provided with means for removably attaching any of these pictures in a position where this picture covers the window 12. For example two horizontal ledges 31 are connected to the back wall 4, run along the upper and lower edge of the window 12 and project slightly into the space behind this window. The film band 25 fits the distance between the ledges 31 and can be so positioned that its front contacts the back side of the wall 4, that its upper and lower rims contact the front sides of the ledges 31 and that a portion of this band covers the window 12. Thus positioned, the band is slidably held and can be moved horizontally whereby any of its pictures may be positioned behind the window 12.

The described toy operates as follows:

In order to simulate X-rays, the frame 13 is moved into that position in which the word "X-Ray" appears behind the aperture 11. In this position of the frame, the window 19 with the feather layer 23 is situated in the line of vision running from the peep-hole 9 to the window 12. The casing 1 is so directed that light enters the window 12, for example, by directing the casing toward a lamp or toward a day-lighted window. A suitable object, for example, a hand with spread fingers is held at a distance behind the casing 1 in the path of the light passing through the window 12 toward the peep-hole 9. When this light passes the feather layer 23, it is deflected or broken in such a peculiar manner that the object held behind the casing casts a shadow consisting of a bright area surrounding a dark kernel with fairly sharp outlines. For example, a finger appears as shown in Fig. 6 where a bright gray area 32 surrounds a dark gray kernel 33. Such a picture is similar to an X-ray picture, the dark part simulating the bones and the bright part the flesh of the finger.

In order to set the toy for the simulation of a microscope, the frame 13 is moved into that position in which the word "Red-Ray" appears behind the aperture 11. This movement brings the window 21 with the colored layer 24 into the line of vision running from the peep-hole 9 to the window 12. Then a suitable transparent picture, for example the picture shown in field 26 of the film band 25 is positioned behind the window 12 in the manner described before, and the casing is directed toward a light source. In the picture observed through the peep-hole 9, the representation of the macroscopic object is blotted out by the layer 24 while the microscopic object appears clearly, its color being strength-

ened by the same layer. For example, the picture of a hand 28 which was well visible before the picture was positioned behind the window 12 disappears, and the germs 29 become clearly visible.

The toy may be alternately used for the simulation of X-rays and of a microscope. The arrangement of two different layers 23 and 24 in windows of one easily movable frame facilitates the transition from one use to the other. These layers are essential for the effects simulated. The casing 1 is helpful in so far as it avoids disturbance of the observed picture by lateral light, provides guidance for the frame 15 and for the film band and increases the similarity to an optic apparatus.

I desire it understood that my invention is not confined to the particular embodiment shown and described, the same being merely illustrative, and that my invention may be carried out in other ways without departing from the spirit of my invention as it is obvious that the particular embodiment shown and described is only one of the many that may be employed to attain the 25 objects of my invention.

Having described the nature of my invention, what I claim and desire to protect by Letters Patent is:

1. An optical toy comprising a frame having 30 a peep-hole, a layer of transparent material of a uniform color positioned across the area of said hole, and a picture showing a macroscopic object represented in said color and further showing a microscopic object represented in a different 35 color and on a much larger scale than said macroscopic object whereby, when said picture is observed through said peep-hole and said transparent layer, the disappearance of said macroscopic object and the clear appearance of 40 said microscopic object simulates the effect of a microscope.

2. An optical toy comprising a camera-like casing having a peep-hole at its front and having an opening at its back, a transparent strip, 45 means affixed to said casing and holding said strip slidably in a position where a portion of said strip covers said opening, a layer of transparent material of a uniform color positioned in the line of vision from said peep-hole to said strip, said strip having a row of pictures, each being not larger than said opening, showing a macroscopic object represented in said color and further showing a microscopic object represented 50 in a different color and on a much larger scale than said macroscopic object whereby, when said picture is observed through said peep-hole and said transparent layer, the disappearance of said macroscopic object and the clear appearance of 55 said microscopic object simulates the effect of a microscope.
